SUSPENSION TRESTLE FOR PLAYGROUND SWINGS

Robert S. Wormser, Mexico, Pa., assignor to The Mexico
Forge, Inc., Mexico, Pa., a corporation of Pennsylvania

Application September 30, 1958, Serial No. 52,824

Term of patent 14 years

(Cl. D34—5)

FIG.1.

FIG.2.

Fig. 1 is a perspective view of a suspension trestle for playground swings, showing my new design.

Fig. 2 is an elevational end view of said trestle, looking at its left end as viewed in Fig. 1.

I claim:

The ornamental design for a suspension trestle for playground swings, substantially as shown.
